FLOAT VALVE STRUCTURE

Stephen Samaras, Oakland, Calif., assignor to
 Samaras Valve Corporation, Oakland, Calif., a
 corporation of California

Application July 12, 1948, Serial No. 38,200

1 Claim. (Cl. 137—437)

1

This invention relates to float valves for automatically controlling the refilling of storage tanks and has particular reference to such a device designed for use specifically in a water closet tank.

An object of the invention is to provide an improved, compact float valve mechanism for a water closet tank or the like.

Another object of the invention is to provide a float-operated valve, for controlling the flow of water into a water closet tank, which is characterized by marked silence of operation.

Still another object of the invention is to provide greatly simplified operating mechanism for actuating a flow-control valve in response to movements of a float.

A further object of the invention is to provide, in apparatus of the character described an improved and simple muffle for minimizing the noise level of operation.

A still further object of the invention is to provide, in a device of the nature referred to, novel valve operating mechanism having one-way action in which, although the valve closes in the direction of water flow, the mechanical advantage of the water pressure transmitted to the float, through the leverage system of the latter, will be so reduced that relative fluttering between the valve and float will not occur and, as a result, chattering of the valve during closing thereof will be eliminated and substantially silent action will obtain.

Still another object of the invention is to provide apparatus of the class described which, although compact in form, is capable of passing a large volume of water in a short time with a resultant rapid filling of the storage tank.

Another object of the invention is to provide a float valve mechanism in which the major parts are constructed of drawn or rolled metal, which lend themselves well to production by presses or rotary cutting machines, or are formed as pressure process castings and therefore are capable of more rapid and economical manufacture and of assembly with a minimum of extraneous fitting operations than are the comparable sand-cast metal parts heretofore used.

Yet another object of the invention is to provide a float-controlled mechanism in which provision is made for rapid removal or replacement as a unit, of the flow-control valve.

The invention possesses other objects and features of advantage, some of which, with the foregoing, will be set forth in the following description of the preferred form of the invention which is illustrated in the drawing accompanying and

forming part of the specification. It is to be understood, however, that variations in the showing made by the said drawings and description may be adopted within the scope of the invention as set forth in the claim.

Referring to the drawing:

Figure 1 is a vertical sectional view of a water closet tank showing the mechanism of my invention included therein. Figure 2 is an enlarged 10 scale vertical sectional view of the upper portion of the valve mechanism shown in Figure 1. Figure 3 is a vertical sectional view taken in the plane indicated by the line 3—3 of Figure 2.

Figure 4 is a horizontal sectional view taken in 15 the plane indicated by the line 4—4 of Figure 2.

In the form in which I have chosen to illustrate my invention I have shown a conventional water closet tank 6 provided with a water supply pipe 7 which enters the tank 6, usually through the bottom thereof, by way of a ferrule fitting 8. Extending from the fitting 8 upwardly into the tank 6 and connected with the supply pipe 7 is a riser pipe 9, and surrounding and concentric with the latter, adjacent its uppermost portion, is a comparatively short discharge tube 11 having at its upper end a radially-extending nipple 12 provided with an axial passage 13 entering the bore of the discharge tube and connected with one end of the usual refill tube 14 whose opposite end is 30 positioned over and may discharge water into the overflow pipe 16 associated with the tank dump valve mechanism 17. The nipple 12 is further provided with an anti-siphoning aperture 15 drilled therethrough and venting the passage 13 to the atmosphere. Although the apparatus of my invention is normally incapable of establishing a siphoning action through the refill tube 14 into the overflow tube, many States have laws making mandatory the provision of vacuum-breaking means in connection with the refill tube and consequently the aperture 15 is provided to conform with these statutory requirements. Mounted in the peripheral space between the riser pipe 9 and the discharge tube 11 and positioned preferably near the lower end of the latter, is a spring diffuser 18 of annular shape serving to break up the stream of water which may issue through the lower end of the discharge tube and further acting in one form of the invention, 40 as a centering means for retaining the riser pipe 9 and the discharge tube 11 in relative concentric position. Retaining means may conveniently be provided for the spring diffuser 18 in a peripheral groove 19 cut internally of the discharge tube and into which the diffuser, after being radially

compressed by insertion into the latter tube, may expand and be thereafter securely held in place.

Disposed at the upper end of the riser pipe 9 and, if desired, formed as an integral part of the discharge tube 11, is a valve housing here shown as being constructed entirely from a unit length of solid metal rod or of tubing of the requisite internal and external diameters, which is formed at its lower end with a hub 21 provided with an axial bore 22 in which is secured, preferably by means of the screw threads 23, the correspondingly threaded upper extremity of the riser pipe. The valve housing is thus fixed to and is supported solely by the riser pipe. The upper portion 24 of the valve housing has an external diameter which is only slightly less than that of the bore of the discharge tube so that the latter tube may be slid axially over and will snugly engage the housing portion 24. The discharge tube is thus centered with respect to the valve housing and is retained in position axially thereof by frictional engagement of the diffuser spring 18 with the external surface of the riser pipe. Also, if desired, the discharge tube may be soldered or pressed onto the portion 24 of the valve housing so as to form an integral unit therewith. The portion 24 of the valve housing, at its upper extremity, is provided with screw threads 26 which engage the corresponding threads of a ring nut 27 having a radially inwardly extending flange 28 overlying the upper end surface 29 of the valve housing. A diametrically reduced portion 32 of the valve housing lies intermediate the hub 21 and the upper housing portion 24 and forms one side of a peripheral passage 33 which provides an upward continuation of the internal passage of the discharge tube to the lower end of the housing portion 24. Internally, the valve housing is provided with an axially-extending recess 34, which is in communication with the upper end of the bore 22, and with an upwardly-continuing and concentric annular space or counterbore 36 of enlarged diameter disposed intermediate the housing portions 24 and 32 and in which is formed an annular shoulder 37 at the junction of the bore and counterbore. Also provided in the upper portion 24 of the valve housing is a plurality of apertures 38 extending radially through the wall section 39 lying between the periphery of the counterbore 36 and the outer periphery of the housing and positioned so that a selected one of the apertures may be aligned with the passage 13 of the refill tube nipple 12 thus bringing the refill tube into communication with the internal space of the valve housing. The valve housing, in the upper portion 24 thereof, is further provided with slits 41 extending vertically from each aperture 38 into the passage 33 so as to provide flow communication therebetween.

In the upper chamber of the valve housing including the counterbore 36 I provide a removable valve unit generally indicated by the numeral 42 which serves to control water flow upwardly from the riser pipe 9 into the upper chamber. The valve may be of any desired construction which will provide the necessary flow control but I prefer to employ the removable barrel-type valve structures shown in either of my prior applications, Serial Number 655,133, filed March 18, 1946, now abandoned, or Serial Number 738,648, filed April 1947, now Letters Patent No. 2,589,630, dated March 18, 1952. Each of these devices comprises, as shown in

Figure 2, a cylindrical barrel 43 slidably fitting in the counterbore 36 and provided at its lower end with a port 44 bordered by a recessed resilient ring 46 which lies partly on the shoulder 37 so as to form sealing means between the barrel and valve housing and which serves when engaged by the vertically movable valve 47 to effect sealing closure of the valve port 44. A spring-pressed stem 48 extending upwardly through the barrel and protruding above the upper end of the valve housing is connected with and to guide the valve 47 axially between open and closed positions. Within the barrel 43 is a chamber 49 in communication with the valve port 44 and with apertures 51 drilled radially through the side wall of the barrel, the outer ends of the apertures opening into a peripheral groove 52 formed exteriorly of the barrel and aligned and communicating with the apertures 38 of the valve housing.

Means is provided for opening and closing the valve 47 in response to changes in the level of the liquid in the tank 6. Disposed above the valve housing is a valve actuator support comprising, preferably, an integral sheet metal member having relatively spaced, parallel and vertically extending side plates 53 having a horizontal tie bar portion 54, disposed substantially intermediate their height, and further provided at their lower ends with horizontally disposed flanges 56 which are arranged to be clamped between the upper end of the valve housing 24 and the overlying flange 28 of the ring nut 27. The outer edges of the flanges 56 are arranged to be clamped at the upper end of the valve housing 24 between the top surface 29 of the valve unit and the overlying flange 28 of the ring nut 27. The outer edges of the flanges 56 are curvate and combine to form a base of generally circular form which may be received within the threaded bore of the ring nut and thereby automatically center the valve actuator support with respect to and above the valve housing. Between the side plates 53 is arranged for vertical sliding movement a U-shaped traveller whose side members 57 overlie and parallel the side plates 53 and whose bottom web 58, which connects the bottom ends of the side members 57, is arranged to immediately overlie the upper end of the valve stem 48. Guide means are provided for the traveller at opposite ends thereof for maintaining the traveller in a vertical path relative to the valve actuator support and in alignment with the valve stem 48. Extending axially horizontally through and journaled in opposed apertures 59 provided in the lower portion of the traveller is a shaft 61 whose outer end portions extend through and are slidable in vertically elongated apertures 62 formed in the side plates 53. The shaft 61 is retained in place, axially, by means of a circular collar 63 pressed thereon and positioned between the side members 57. The upper ends of the side members 57 are each provided with vertically extended notches 64 in which is slidably received an axially horizontal shaft 66 whose opposite end portions are journaled in axially aligned apertures 67 provided at the upper ends of the side plates 53 and whose central portion is pressed into a lever 68 lying between the side members 57 of the traveller. A lower edge portion of the lever 68 is shaped to form a curvate cam 69 substantially of cycloidal form whose rise progresses from a minimum dimension in a plane normally traversing the longitudinal ex-

tent of the lever to a maximum dimension in a plane substantially normal to said first plane. As shown in Fig. 2, the cam 69 is arranged to bear against the periphery of the collar 63 which functions as an anti-friction roller for the cam. The distal end of the lever is provided with an integral sleeve 71 created preferably by bending opposed side portions of the lever to conjunctively form a cylinder. The sleeve 71 is provided with internal threads for receiving the correspondingly threaded rod arm 72 to the distal extremity of which is attached the ball float 73 buoyed by the water in the tank.

After the tank has been emptied of water, the float 73 will have descended to its lowermost position of travel and as a result the cam 68 will have been rocked downwardly to cause the traveller 51, 58, 57 to descend thereby depressing the valve stem 48 and moving the valve 47 downwardly to uncover the valve port 44. Water may then flow from the riser pipe 9, pass through the open valve port into the chamber 49 and then flow through the apertures 51 and 38, and the vertical grooves 41, into the discharge tube 11 to thereafter pass downwardly through the diffuser 18 and enter the tank to refill the latter. It will be noted that regardless of the volume of flow issuing from the discharge tube, the usually solid stream will be broken up by the diffuser 18 and will fall with less concentrated force into the body of water residing in or previously discharged into the tank. Thus the noise which usually follows the introduction of a solid forceful stream into a hollow container is greatly reduced. It will also be noted that the shape of the cam 69 permits comparatively rapid opening and closing movements of the valve 47, in proportion to movements of the cam responsive to receding or rising water levels in the tank, toward the end of the valve opening movement and at the start of the closing operation of the valve. It will be observed that water issuing from the riser pipe 9 impinges against the face of the valve 47 and urges the latter to close in the direction of water flow. Under such conditions, the leverage systems usually employed in connecting the valve for operation by the float are easily influenced by the aforesaid water pressure and frequently set up sympathetic vibrations between the valve and float which emanate audibly from the outer surfaces of the tank and transmitted, by conductance along the pipes, throughout the entire water system of the dwelling. This, in a large measure, is responsible for the noisy operation of the usual water closet tank. In the cam arrangement of my invention it will be seen that as the valve 47 approaches its closed position the cam lever 68 will have moved to a position substantially rectangularly related to the path of movement of the traveller so that the mechanical advantage existing between the traveller and cam is reduced to such an extent that insufficient force will be exerted by the valve, due to the water pressure thereon, to transmit movement to the arm 72 or the float 73. Consequently, the closing of the valve will be accomplished without chatter or induced vibra-

tions and will be marked by the substantially complete absence of noise.

5 Servicing of the apparatus above described is comparatively simple. The only part which may require periodic attention is the removable valve unit and the separation or replacement of the latter unit may be readily effected by the act of detaching or reattaching the ring nut 27, the valve actuator support in the former case, being then separated from the valve housing so that the valve unit is exposed and may be readily lifted from the housing.

10 Manufacture of the apparatus of my invention is greatly simplified and rendered more economical since, it is seen, a great many of the major parts may be constructed of sheet or rod material or tubing of the requisite sizes or, in the case of the valve body, the latter may be combined with the discharge tube to form a unitary die-cast member so that fabricating operations may be rapidly and efficiently carried out on punch presses, automatic turning machines and pressure molding apparatus. Such simplified structure and fabricating operations greatly reduce production costs and will combine to effect measurable savings to the ultimate consumer.

15 I claim:

20 In a liquid-receiving tank including a substantially vertical riser pipe through which liquid may flow to enter said tank, a liquid discharge tube surrounding and concentric with the upper end portion of said riser pipe and removable therefrom, said tube having the lower end thereof open to the interior of said tank, means interposed between the outer periphery of said riser pipe and the inner peripheral surface of said discharge tube adjacent the lower end of the latter for retaining said pipe and tube in relative concentric relation, a valve housing having an inlet communicating with said riser pipe and an outlet through which liquid entering said valve housing may flow, said outlet terminating within said discharge tube whereby liquid flowing therefrom will pass through said tube and discharge at the lower end thereof.
